DESIGN FOR AN OPHTHALMIC MOUNTING

Jacob Kane, Rochester, N. Y.

Application February 23, 1934, Serial No. 50,831

Term of patent 14 years

To all whom it may concern:

Be it known that I, JACOB KANE, a citizen of the United States, residing at Rochester, in the county of Monroe and State of New York, have invented a new, original, and ornamental Design for an Ophthalmic Mounting, of which the following is a specification, reference being had to the accompanying drawing, forming part thereof.

In the drawing:

Fig. 1 is a front view of an ophthalmic mounting, showing my new design, and

Fig. 2 is a plan view thereof with the ends of the temples broken away for convenience of illustration.

I claim:

The ornamental design for an ophthalmic mounting, as shown.

JACOB KANE.
